CLAIM

The ornamental design for intelligent virtual reality glasses, as shown and described.

DESCRIPTION

FIG. 1 is a perspective view of intelligent virtual reality glasses showing our new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.

The broken lines in the drawings depict portions of the intelligent virtual reality glasses that form no part of the claimed design.
